UNITED STATES PATENT OFFICE.

EMIL T. NEBEN, OF BROOKLYN, NEW YORK, ASSIGNOR TO PARAGON FIBRE COLORING CORPORATION, OF NEW YORK, N. Y., A CORPORATION OF NEW YORK.

MULTICOLOR-PRINTING MACHINE.

1,199,709.

Specification of Letters Patent. Patented Sept. 26, 1916.

Application filed October 12, 1912. Serial No. 725,373.

To all whom it may concern:

Be it known that I, EMIL T. NEBEN, a citizen of the United States of America, and resident of the city of Brooklyn, county of 5 Kings, and State of New York, have invented certain new and useful Improvements in Multicolor-Printing Machines, of which the following is a specification.

My invention relates to multi-color printing machines.

The object of my invention is to provide a machine for printing surfaces of various descriptions, such as a web of paper or fabric or other substance that may be moistened on the surface, either in a continuous roll or sheets, in variegated colors, and to produce a novel printed surface thereon by means of my improved printing machine and has not, so far as I am aware, been produced heretofore.

My invention consists in providing a printing member either in the form of a roll or plate or bar, composed of a soluble variegated composition; in providing means for 25 feeding the surface to be printed across or in contact with said printing member, either in slipping contact or non-slipping contact as may be desired; in providing means for supplying moisture in regulated amounts to 30 the surface to be printed; in providing means for varying the effect of the printing by changing the relative speeds of the printing member and of the printed surface; and in other novel features and constructions to be hereinafter more fully pointed out and described.

In the drawings accompanying and forming part of this specification Figure 1 is a side view of the preferred form of a multi-color printing machine embodying my invention; Fig. 2 is a front view of the same; Fig. 3 is a partial section on line 3—3 of Fig. 1; Fig. 4 is a partial section on line 4—4 of Fig. 1; Fig. 5 is an end view of the nut 20; and Figs. 6 and 7 are side and rear views respectively of a modified form of the machine.

Numeral 1 represents the side frame of the machine, secured to which are the brackets 2, which form a support for a roll 3 of paper or other material, the surface of which is to be printed. The material from the roll 3 is led over a guide roll 4 and around the impression roll 5. The roll 5 is

mounted on the shaft 6, which is journaled in the bearings 7. The impression roll preferably has a covering 8 of vulcanized rubber, in order to make better contact with the web 3. The roll is driven by a chain 9 operating on the chain wheel 10, secured to the shaft 6 and connected with any convenient source of power. Mounted in vertical guides 11 of the frame, are the bearings 12, in which is journaled the shaft 13, which carries the printing roll 14. The printing roll 14 preferably consists of a composition which is relatively hard and tough and possesses such a degree of solubility that when it comes in contact with a moistened surface it readily gives up its color thereto, and it is generally composed of a number of differently colored masses of composition variously arranged and molded together into a compact form, so as to produce a variegated or vari-colored mass.

The bearings 12 are provided with extensions 15 having threaded holes in their ends, and the sleeves 16 are provided with oppositely threaded holes in their lower ends. A screw 17 having a right hand thread at one end and a left hand thread at the other engages the sleeve 16 and the extension 15 of the bearing 12, and by means of these screws the printing roll 14 may have its ends adjusted independently so as to bring it into proper alinement with the impression roll 5. The upper ends of the sleeves 16 are provided with transversely milled grooves 18 which engage the lugs 19 on the nut 20, so that the sleeves 16 are prevented from turning and are carried up and down with the nut 20 and may be readily disengaged from the nut 20. The upper portions of the nuts 20 are rectangular in section and enter a rectangular hole in the transverse web 21 of the cap 22. The caps 22 are provided at their ends with pins 23 on which are pivotally secured the clamps 24 which, by means of the thumb screws 25, hold the caps 22 in position on the frame. The screws 26 have beveled pinions 27 secured to their upper ends and having their lower ends in threaded engagement with the nuts 20, are operated by the pinions 28 on the shaft 29, having a handle 30 secured to its end. By means of this construction both ends of the printing roll may be simultaneously raised or lowered.

Secured on the shaft 13, on which the printing roll 14 is mounted, is the gear 31, which is adapted to mesh with the gear 32 on the shaft 33. The gear 32 is provided with a grooved hub 34, and it is connected to the shaft 33 by means of a feather which causes the gear to turn with the shaft and permits the gear to slide upon the shaft into and out of engagement with the gear 31. 5
 10 The operating lever 35 pivotally mounted in the bracket 36 and having a forked end 37 engages the grooved hub 34 to effect the engagement and disengagement of the gear 32 with the gear 31. 15
 15 The shaft 33 is rotatably mounted in the bracket 38 and has the worm gear 39 secured to its end. The shaft 40 carrying the worm 41 which engages the worm gear 39, is mounted in brackets secured to the frame 20 of the machine and has secured to it a cone pulley 42 connected by the belt 43 to the cone pulley 44 on the shaft 45. A belt pulley 46 also mounted on the shaft 45 is connected by a belt 47 to a pulley 48 secured to the end of the shaft 6. By means 25 of these connections, when the gear 32 is thrown into engagement with the gear 31, the printing roll 14 will be caused to revolve at a speed relative to the speed of the impression roll 5, depending upon which step 30 of the cone pulleys the belt 43 rests, and in general I prefer to have all of the speeds resulting from this connection proportioned so as to give a slower peripheral speed to 35 the printing roll than the peripheral speed of the impression roll. It will be readily understood that the impression roll 5 serves the purpose of bringing the paper into printing contact with the printing roll and the 40 further purpose of feeding the paper across the face of the printing roll. When it is desired to have the periphery of the printing roll travel at the identical speed of the periphery of the impression roll, the lever 45 35 is operated to throw the gear 32 out of engagement with the gear 31, and the printing roll is then caused to revolve by its frictional engagement with the paper and impression roll. The printing roll will then 50 print upon the paper the exact design corresponding to the arrangement of the differently colored masses which compose the roll. When, however, the printing roll is caused to revolve at a slightly slower peripheral speed the design will be somewhat elongated and a marbleized effect will be 55 produced, and when the printing roll is given a very much slower peripheral speed, or if it is held stationary various streaked 60 effects are produced.

Below the impression roll 5 each side of the frame is provided with a vertical slot 49, in which is mounted a bearing 50 supporting the shaft 51, on which the moistening roll 52 is mounted. This roll is pref-

erably covered with felt and its lower edge dips into the tank 53 which contains water. A cap 54 bolted to the frame across the lower end of the vertical slides 49, carries the screw 55, which is in threaded engagement with the bearing 50 and has a bevel pinion 56 secured to its lower end. This beveled pinion meshes with the beveled pinion 57 secured to a shaft 58, at the end of which is secured an operating handle 59, by means of which the moistening roll 52 may be raised and lowered. In order that the amount of moisture or water carried by the moistening roll 52 up against the surface of the paper which passes around the impression roll 5 may be regulated, I provide a roll 60 mounted in an oscillating frame 61, said frame being pivoted on the shaft 62, which shaft has bearings in the side frame 1. The shaft 62 projects through one of the side frames and has secured to its end a lever 63 and a screw 64 is in threaded engagement with the lug 65 on the frame and has a hand wheel 66 secured to its end, and passes through a hole in the end of the lever 63 and is provided with collars 67 on either side of the lever, by means of which the regulating roll 60 may be moved into and out of contact with the moistening roll 52, or the amount of pressure of the regulating roll upon the moistening roll may be varied so as to permit the moistening roll to carry more or less water up to the paper, as may be required.

In the modification shown in Figs. 6 and 7, the variegated printing composition is molded in the form of a plate or bar, and held in a receiver in contact with the surface to be printed upon as the latter is passed under it in a moistened condition. In this embodiment of my invention, in lieu of the cylindrical printing roll 14, I provide a flat bar or plate 68 composed of the same composition in variegated colors. This plate is received into the chamber 69 between the transverse plates 70, and its lower edge rests upon the surface or web 3 which is to be printed. The upper end of the composition plate 68 has secured to it by means of the clamps 71 or otherwise, flexible cords 72 which pass over the pulleys 73, where they are secured to the counter-weights 74. The counter-weights 74 may be increased or diminished to give the appropriate pressure between the composition plate 68 and the web 3. By means of this construction a great variety of novel and pleasing streaked effects is produced, at a very small expense.

Having thus described my invention, what I claim is:

1. A multicolor machine for producing fancy variegated designs on a moving moist web of paper or textile fabric, comprising an impression roll rotatably mounted in a fixed position, a compact variegated printing roll

- rotatably mounted and contacting with the moist passing web, and means for driving the printing and impression rolls at different peripheral speeds.
- 5 2. A multicolor machine for producing fancy variegated designs on a moving moist web of paper or textile fabric, comprising an impression roll rotatably mounted in a fixed position, a compact variegated printing roll 10 rotatably mounted and contacting with the moist passing web transported by the impression roll, and means for driving the printing roll at a lower speed than the said impression roll.
- 15 3. A multicolor machine for producing fancy variegated designs on a moving moist web of paper or textile fabric, comprising an impression roll rotatably mounted in a fixed position, a compact variegated printing roll 20 of less diameter than the impression roll, rotatably mounted and contacting with the moist passing web, and means for driving the said impression roll and the said printing roll at different peripheral speeds.
- 25 4. A multicolor machine for producing fancy variegated designs on a moving moist web of paper or textile fabric, comprising an impression roll rotatably mounted, a compact variegated printing roll rotatably 30 mounted and contacting with the moist passing web, means for driving the impression
- roll at a fixed speed, and means for driving the printing roll at variable speeds.
5. A multicolor machine for producing fancy variegated designs on a moving moist 35 web of paper or textile fabric, comprising an impression roll, a compact variegated printing roll rotatably mounted and contacting with the moist passing web, means for driving the printing roll at variable 40 speeds, and means for releasing the means producing variable speeds so that the printing roll is rotated by friction with the impression roll.
6. A multicolor machine for producing 45 fancy variegated designs on a moving moist web of paper or textile fabric, comprising an impression roll, a printing roll with compact variegated printing surface cylinder, gear connections to drive the printing roll at 50 variable speeds different from the speed of the impression roll, and means for releasing the gears allowing the printing roll to rotate by friction with the impression roll.

In testimony whereof, I have signed my 55 name to the specification in the presence of two subscribing witnesses.
